(57) **CLAIM**

The ornamental design for a multi detector radiological source jig, as shown and described.

DESCRIPTION

The invention was made with government support under Contract No. DE-AC05-00OR22725 awarded by the U.S. Department of Energy. The government has certain rights in the invention.

FIG. 1 is a perspective view of a multi detector radiological source jig showing our new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a rear view thereof; and,

FIG. 7 is a front view thereof.

The broken lines in the drawings depict portions of the multi detector radiological source jig that form no part of the claimed design.
